UNITED STATES PATENT OFFICE.

JOHN WESLEY FERGUSON, OF BLOOMFIELD, NEW JERSEY.

DESIGN FOR A FLAT-IRON STAND.

48,632.

Specification for Design.

Patented Feb. 29, 1916.

Application filed January 21, 1916. Serial No. 73,469. Term of patent 7 years.

To all whom it may concern:

Be it known that I, JOHN WESLEY FERGUSON, a citizen of the United States, residing at Bloomfield, in the county of Essex and State of New Jersey, have invented a new, original, and ornamental Design for Flat-Iron Stands, of which the following is a specification, reference being had to the accompanying drawing, forming part thereof.

The figure is a plan view of a flat-iron stand, showing my new design.

I claim:

The ornamental design for a flat-iron stand as shown.

JOHN WESLEY FERGUSON.

Witnesses:

PETER J. QUINN,
ADELE FREY.
